UNITED STATES PATENT OFFICE.

ADAM HEIM, OF BROWNSVILLE, INDIANA.

COMBINED CONVEYER AND ELEVATOR.

No. 829,648.

Specification of Letters Patent.

Patented Aug. 28, 1908.

Application filed June 21, 1905. Serial No. 266,242.

To all whom it may concern:

Be it known that I, ADAM HEIM, a citizen of the United States, residing at Brownsville, Indiana, have invented a new and useful Improvement in a Combined Conveyer and Elevator, of which the following is a specification.

My invention relates to combined conveyers and elevators of the class adapted to use in mines or elsewhere for moving and delivering phosphates, ores, or other material; and the objects of my improvement are to provide endless troughs with wheels movable on stationary tracks, to form the troughs of a series of sections hinged together, to provide rectangular drums to drive the troughs, to support the frames on runners to facilitate their lateral movement, and to so construct and assemble the parts as to combine efficiency with durability.

These objects are attained in the following described manner, as illustrated in the accompanying drawings, in which—

Figure 1 is a side elevation of a conveyer and elevator embodying my improvement; Figs. 2 and 3, respective sections in perspective of the elevator and conveyer troughs; Fig. 4, a transverse section of the conveyer; Fig. 5, a side elevation of the troughs and tracks; Figs. 6 and 7, details of construction of the trough-section hinges; Figs. 8 and 10, longitudinal sections, respectively, of portions of the conveyer and elevator; and Fig. 9, a transverse section on the line *a a* of Fig. 8.

In the drawings, 11 represents the body of the conveyer provided with side sheathings 12 and supported on transverse sills 13 by means of legs 14, which are provided with braces 15. The ends of the sills are turned upward to facilitate the lateral adjustment of the elevator on the ground toward the material to be placed therein. Slanting surfaces 16 are secured on the sides of the body to prevent the material from falling outside of the endless trough 17. Said trough consists of a series of an odd number of pans or sections 18, connected together with hinges 19 and mounted to travel on upper and lower tracks 20 and 21 by means of flanged wheels 22, secured on the sides of either successive or alternate pans. The ends of said tracks, respectively, overlap each other to prevent the lateral displacement of the flanged wheels

in their passage from one to the other. One end 23 of the sides of each pan extends along the outside of the contiguous pan to form continuous sides to the endless trough between the pans in its travel around front and rear drums 30 and 24. Said drums are similar and rectangular in cross-section, with each side approximately equal in width to the distance between adjacent hinges 19, and they are journaled between the ends of the tracks in the ends of the body 11.

To maintain the tension of the endless trough approximately constant, it is so arranged that the drums are always in different positions, amounting to one-eighth of a turn or rotation.

Pulley 25, driven by a belt from a source of power, (not shown,) transmits motion through pinion 26 and gear-wheel 27 in mesh therewith to the rear drum 24, whereby the endless trough 35, which preferably consists of an odd number of sections, is caused to travel on the tracks and discharge the material placed thereon within the lower end of the elevator 28. Said elevator is adjustably supported at one end on extension-legs 29 and swiveled at the other end on shaft 31 of a rectangular drum therein, (shown in Fig. 10,) similar to drum 24. Sprocket-chain 32 transmits motion from sprocket-wheel 33, secured on the shaft of drum 24 to sprocket-wheel 34, secured on shaft 31, which causes the drum secured thereon to actuate the endless trough 35 in the elevator, which is formed with transverse partitions 36 in each of the preferably odd number of sections of which it is formed to facilitate the elevation of the material therein. The construction of the elevator is similar to that of the conveyer in all respects, except the omission of the legs from beneath its body portion and the addition of the transverse partitions 36. The body portions, together with the endless troughs, may be constructed in a manner to be separable into sections of such length as may be convenient for removal from place to place.

In operation the conveyer is placed alongside a bank of coal, ore, or other material which may be shoveled therein and delivered in a car or wagon from the elevator. It may be adjusted laterally from time to time to maintain its position of convenience to the material to be removed.

aving fully described my improvement, what I claim as my invention, and desire to secure by Letters Patent of the United States, is—

- 5 1. The combination with a horizontal frame, superposed tracks with overlapping ends supported thereby, and rectangular drums journaled in the frame between the ends of the tracks, said drums being always
- 10 in different positions amounting to one-eighth of a rotation, of an endless trough consisting of a series of hinged sections extending around the drums, and flanged wheels secured to the trough and movable
- 15 on the tracks.
2. The combination with an adjustably inclined elevator, of transverse ground-sills formed with upturned ends, for the purpose specified, superposed tracks horizontally
- 20 supported thereon, rectangular drums jour-

naled between the end portion of the tracks, an endless trough arranged to travel around the drums and discharge into the elevator, and flanged wheels thereon movable on the tracks.

- 25 3. The combination with a conveyer, of an adjustably-inclined elevator consisting of rectangular drums, always being in different positions of rotation amounting to one-eighth of a turn, an endless trough carried thereby and formed of a series of hinged sections, a transverse partition in each section, parallel tracks with overlapping ends extending between the drums, and flanged wheels movable thereon attached to the
- 30 trough.
- 35

ADAM HEIM.
